(57) **CLAIM**

The ornamental design for a headset, as shown and described.

DESCRIPTION

FIG. 1 is a front and right side perspective view of a headset showing our new design;

FIG. 2 is a top plan view thereof;

FIG. 3 is a front elevational view thereof;

FIG. 4 is a right side elevational view thereof;

FIG. 5 is a left side elevational view thereof;

FIG. 6 is a rear elevational view thereof;

FIG. 7 is a bottom plan view thereof;

FIG. 8 is a front and right side perspective view of an alternate embodiment of FIG. 1;

FIG. 9 is a top plan view of FIG. 8;

FIG. 10 is a front elevational view of FIG. 8;

FIG. 11 is a right side rear elevational view of FIG. 8;

FIG. 12 is a left side elevational view of FIG. 8;

FIG. 13 is a rear elevational view of FIG. 8; and,

FIG. 14 is a bottom plan view of FIG. 8.

The broken line showing of the boom and wearer in FIGS. 1 and 8 is for illustrative purposes only and forms no part of the claimed design.
